UNITED STATES PATENT OFFICE

HENRY J. COLE, OF GAINESVILLE, TEXAS.

SAND-MILL TOY.

1,213,076.

Specification of Letters Patent. Patented Jan. 16, 1917.

Application filed October 13, 1916. Serial No. 125,481.

To all whom it may concern:

Be it known that I, HENRY J. COLE, a citizen of the United States, residing at Gainesville, in the county of Cooke and State of 5 Texas, have invented new and useful Improvements in Sand-Mill Toys, of which the following is a specification.

This invention relates to toys and has particular reference to figure toys, wherein motion is transmitted from a sand wheel motor to one or more of said figures causing the latter to give imitations of a person dancing.

The invention aims to provide a toy of the 15 above mentioned character wherein the component parts are so designed to permit of their construction from cheap material, thus producing a toy which in addition to being efficient for the purpose intended can be 20 manufactured and sold at a minimum cost.

The nature and advantages of the invention will be better understood from the following description when taken in connection with the accompanying drawing, the 25 invention residing in the construction, combination and arrangement of parts as claimed.

In the drawings forming part of this specification like numerals of reference indicate similar parts in the several views and wherein:—

Figure 1 is a front elevation of the toy constructed in accordance with my invention. Fig. 2 is a top plan view. Fig. 3 is 35 a vertical sectional view. Fig. 4 is a horizontal sectional view. Fig. 5 is an enlarged view of the motor shaft. Fig. 6 is a similar view of the figure supporting element.

40 A toy constructed in accordance with my invention embodies a receptacle indicated at A, which may be constructed from any suitable material and configuration, it being however preferably of rectangular formation. The receptacle is divided by means of a vertical partition 10 into two compartments 11 and 12 respectively, while the latter compartment is subdivided by a horizontal partition 13 as shown. Suspended 45 beneath the partition 13 are two figures, the arms and limbs of which are loosely connected to the body portion so that the figures will give indications of persons dancing when motion is imparted to the figures in 50 the manner to be hereinafter more fully described. The front wall of the receptacle

has an enlarged opening through which the figures may be seen to perform, and if desired this opening can be covered by some suitable transparent material, although this 60 is not necessary.

Fixed between the front wall of the receptacle and the vertical partition 10, at an appropriate distance above the horizontal partition 13 is a fixed shaft 15 upon which 65 is loosely mounted the element which constitutes the support for the figures. This element is preferably formed from a single length of wire to provide a substantially U-shaped portion 16 which depends from the 70 shaft 15, the parallel limbs of the U-shaped portion being coiled about the shaft as at 17, and terminating to provide laterally projecting arms 18. One of the coils 17 is extended in parallelism with the shaft 15 75 to dispose the arms 18 in horizontal alignment. The figures above referred to are suspended from the terminals of the arms 18 through the instrumentality of flexible elements 19, which elements are passed 80 through suitable openings in the partition 13. The supporting element for the figures is mounted upon the shaft 15 for rocking movement and is actuated in the manner to be presently described.

85 Journaled between the rear wall of the receptacle and the vertical partition 10 is a shaft 20 and upon which is fixed a sand wheel 21, which latter is disposed immediately beneath the hopper 22 supported upon 90 the upper edge of the receptacle and vertical partition 10. One end of the shaft 20 extends an appreciable distance into the compartment 12 above the partition 13, and is looped to provide a substantially triangular shaped actuating portion 23 for imparting 95 a rocking motion to the figure supporting element on the shaft 15. The U-shaped portion 16 of this element has its lower edge disposed in the path of movement of the triangular-shaped member to be successively 100 engaged by the limbs of the latter as the shaft 20 is rotated, consequently rocking the figure supporting elements to maintain the figures in continuous movement while the 105 shaft 20 is being rotated, the figures being constructed as above stated in a manner to represent persons dancing or jiggling. It is of course to be understood that sand is poured in the hopper 22 from which it is 110 discharged upon the sand wheel to cause rotation of the latter together with the shaft

20, the sand falling from the wheel upon a discharge chute 25 leading through the rear wall of the receptacle for the purpose of discharging the sand into a suitable receptacle 5 which can be positioned beneath the chute. The receptacle is closed by means of a cover 26 which is preferably hinged upon one wall of the receptacle, the cover being provided with an enlarged opening 27 disposed above 10 the hopper so that sand can be introduced into the hopper without necessitating the lifting or opening of the cover 26. When the cover is closed the entire operating mechanism is wholly concealed from view, and if 15 desired, the cover may be locked or held closed in any suitable manner to prevent young children from gaining access to the interior of the receptacle and tampering with the mechanism. The shaft 20 may be 20 constructed from a single length of wire the same as the shaft 15 and the supporting element for the figures, it being manifest that the component parts of the toy in its entirety being designed to permit of their construction from such material which materially reduces the cost of manufacture and 25 sale of the article to a minimum. The toy is very simple in its make-up, and operates to afford unlimited amusement to young children.

What is claimed is:—

1. A toy of the character described comprising a receptacle, a partition dividing the receptacle into compartments, a sand wheel 35 journaled in one of said compartments, movable figures suspended in the other of said compartments, an element supporting said figures and mounted for rocking movement, and an actuating member carried by the 40 shaft of said wheel and disposed in the last mentioned compartment to rock said element upon rotation of the wheel.

2. A toy of the character described comprising a receptacle, a partition dividing the 45 receptacle into compartments, a shaft journaled in one of said compartments, a sand wheel fixed upon the shaft, an element arranged within the other compartment for rocking movement and actuated by the adjacent 50 terminal of said shaft, movable figures

ures suspended from said element, and a hopper disposed within the first mentioned compartment above said wheel.

3. A toy of the character described comprising a receptacle, a partition dividing the 55 receptacle into compartments, a shaft journaled in one of the compartments, and extending a slight distance within the other compartment, a sand wheel fixed upon the shaft, an element arranged within the last 60 mentioned compartment for rocking movement and actuated by the adjacent terminal of said shaft, movable figures suspended from said element, a hopper disposed within the first mentioned compartment above said 65 wheel, and a cover closing the receptacle and having an opening immediately above said hopper.

4. A toy of the character described comprising a receptacle, a partition dividing the 70 receptacle into compartments, a fixed shaft in one of the compartments, an element mounted upon the shaft for rocking movement and embodying a pair of laterally disposed arms, movable figures suspended from 75 said arm, a shaft journaled in the other compartment and projecting within the first mentioned compartment to actuate said element, a sand wheel fixed upon the last mentioned shaft, and a hopper disposed above 80 said wheel.

5. A toy of the character described comprising a receptacle, a partition dividing the receptacle into compartments, a shaft journaled in one of the compartments and having 85 an angular shaped terminal disposed within the other compartment, a sand wheel fixed upon the shaft, a second shaft in the other of said compartments, an element constructed from a single length of wire mounted upon the shaft for rocking movement, and formed to provide a pair of laterally disposed arms, and a portion disposed in the path of movement of the angular shaped terminal of the first mentioned shaft to be 90 actuated thereby, movable figures suspended from said arms, and a hopper arranged within the receptacle above said wheel.

In testimony whereof I affix my signature.
HENRY J. COLE.
